C. F. McCANN

SLOW CLOSING FAUCET

Filed Nov. 22, 1926

Inventor

Clyde F. McCann

UNITED STATES PATENT OFFICE.

CLYDE F. McCANN, OF SAN FRANCISCO, CALIFORNIA.

SLOW-CLOSING FAUCET.

Application filed November 22, 1926. Serial No. 148,996.

The object of this invention is to provide a simple and reliable slow closing means for a faucet or valve.

In the wash-rooms of hotels and public places, it is the custom to install extensively self-closing spring faucets. These conserve the amount of water used, but are very inconvenient to the user on account of the quick closing action of the spring faucet. It would be of considerable convenience to the user to have a faucet which when turned on would remain open for a period of time before closing itself. This would allow time for washing, etc. There have been a number of slow-closing faucets on the market which operate on the by-pass valve principle, allowing the water in a chamber in the faucet to run thru a very small opening. This type of faucet is expensive to manufacture and also unreliable in operation, due to clogging of needle valve or by-pass valve with alkali, etc.

In this invention, a very simple and reliable slow closing means for a faucet or valve has been provided in the form of a water-bellows, which is situated below and against the faucet valve in a special water chamber. When the faucet handle is forced down, this opens the valve and at the same time compresses the water-bellows. This compression forces the water out quickly thru a small valve in the bellows. The handle is then released and a spring in the bellows gradually extends the bellows as the water in the chamber seeps thru the side walls to fill the partial vacuum thus created. As the bellows extends, it forces the valve to slowly close until a water shut-off is accomplished.

Referring to the drawing, the figure shows a side view cross-section of the slow-closing faucet. The faucet is shown in cross-section on its central plane, revealing the water passages, water chamber, bellows cartridge, valve, valve stem and handle, etc.

1 is inlet passage for the water. 2 is outlet or nozzle of faucet. 3 is a special cylindrical water chamber or container for slow-motion bellows cartridge. 4 is a threaded water-tight cap which screws up on cyl-

inder 3. 5 is the valve seat. 6 is a rubber plug valve. 7 is the valve stem. 8 the push handle. 9 is a water-tight bushing for valve stem. 10 is a screw collar which screws onto casing 11, of the faucet. 12 is the bellows cartridge which supplies the slow closing motion to the valve and valve stem. This cartridge is a compression bellows and is loosely placed in water chamber 3 and unattached to any of the other members of the faucet. The cartridge consists of the parts as follows. 13 is the top cap of the cartridge shown in side view. 14 is the bottom cap of the cartridge shown in cross-section. 15 is the flexible semi-porous fabric wall of the cartridge. The walls are continuous from top to bottom and cemented to the caps, but are here shown partially cut away. 16 is a compression spring shown inside the flexible walls, which bears against the inside of the top and bottom caps of the cartridge. This pressure tends to keep the side walls 15 stretched or extended normally. In the bottom of cap 14 is a small opening or water passage 17. A small flap valve 18 keeps this opening normally closed. Normally, the valve 6 is pressed upward by spring 16 against valve seat 5, thus shutting off the water from passage 2. In the drawing, however, the valve 6 is shown slightly depressed for the sake of clearness. Bellows 12 is normally filled with water.

The operation of the faucet is as follows. Push-handle 8 is depressed which compresses and shortens bellows cartridge 12, thus compressing spring 16 and wrinkling or folding side walls 15. Since the bellows was full of water, this compression drives a considerable portion of the water out thru hole 17 past flap valve 18. The depression of valve 6 allows the water from inlet 1 to flow thru port 19 and out thru nozzle 2. The handle 8 is now released. This relieves the pressure on cartridge bellows 12 and allows spring 16 to expand the bellows. This expansion creates a partial vacuum in the bellows which closes valve 18 against the entrance of water into the bellows. However, the side walls 15 of the cartridge are slightly porous, so that the water in chamber 3

gradually seeps thru to the inside of the bellows. This seeping action allows spring 16 to gradually extend the bellows and force valve 6 upward until it presses against seat 5 and shuts off the flow of water in 2, thus turning off the faucet.

In this slow-closing faucet invention, the cartridge bellows supplies the slow-closing shut-off to the valve, and the novelty of the 10 invention resides solely in this water-bellows and in its combination with the valve parts of the faucet. However, this cartridge bellows is applicable to other slow motion mechanisms such as time-element electrical 15 relays etc. Also the bellows may function in other mediums such as oil for example.

It is to be noted that by unscrewing cap 4, cartridge 12 can easily be removed and another one substituted in its place in case 20 of wear, etc. Also by making cartridges with walls of different porosity, various closing times can be obtained.

As shown in the drawing, the slow motion bellows, when acted upon by the hand 25 push rod, compresses and drives part of the contained water thru a one-way valve into the water chamber. When expanding under the action of its compression spring, the bellows draws water from the chamber to the 30 inside thru the porous walls, giving a slow motion expansion. The bellows, however, could be designed on the same principle, but working in a reverse manner. That is, the bellows could be normally contracted in 35 stead of expanded, by using a tension spring instead of a compression spring. Also the small bellows valve could be reversed, allowing water to be quickly drawn in when the bellows is extended by the action of a pull 40 rod attached to it. Upon release, the bellows would slowly contract under the force of the tension spring and drive the water thru its walls into the water chamber, thus giving the required slow motion to the at- 45 tached rod.

While I have shown and described the preferred embodiment of my invention, I 50 wish it to be understood that I do not confine myself to the precise details of the construction herein set forth, by way of illustration as it is apparent that many changes and variations may be made therein by those skilled in the art, without departing or exceeding the scope of the appended claims.

55 I claim:

1. In a slow closing valve mechanism, a valve operable by a hand push rod, a bellows, a fluid chamber containing the bellows and communicating with the fluid inlet, the 60 side walls of the bellows of flexible porous material allowing slow entrance of fluid from chamber thru walls into bellows, a pair of opposed rigid caps mounted on the bellows axially with the push rod, a compres- 65 sion spring within the bellows acting be-

tween the two caps to normally expand the bellows and force the valve into the valve seat, a valved opening in one cap for allowing quick passage of fluid out of the bellows into fluid chamber upon compression of bellows by action of the push rod.

2. In a slow closing valve mechanism, a fluid chamber communicating with the fluid inlet, a bellows within the fluid chamber whose expansion supplies a slow closing motion to the valve, walls of the bellows of flexible porous material allowing slow entrance of fluid from chamber thru walls into bellows, a compression spring within the bellows for expanding the bellows and for supporting the flexible walls, a valved opening in bellows for allowing quick passage of fluid out of bellows into fluid chamber upon compression of bellows during opening of valve mechanism.

3. In a slow motion mechanism, a fluid chamber, a bellows within the fluid chamber whose expansion supplies a slow motion to a desired movable member, walls of bellows of flexible porous material allowing slow entrance of fluid from chamber thru walls into bellows, a compression spring for expanding the bellows, a valved opening in bellows for allowing quick passage of fluid out of bellows into fluid chamber upon compression of bellows.

4. In a slow motion mechanism, a fluid chamber, a bellows within the fluid chamber whose expansion supplies a slow motion to a desired movable member, walls of bellows of flexible porous material allowing slow entrance of fluid from chamber thru walls into bellows, a compression spring within bellows for expanding the bellows and also for supporting the flexible walls, a valved opening in bellows for allowing quick passage of fluid out of bellows into fluid chamber upon compression of bellows.

5. In a slow motion mechanism, a fluid chamber, within the fluid chamber a spring actuated bellows having means for allowing a quick exhaust of fluid from the bellows on compression and allowing slow intake to the bellows on expansion, an external member operated by the motion of the bellows.

6. In a slow motion mechanism, a fluid chamber, within the fluid chamber a spring actuated bellows, an external member for operating the bellows and when released operated by the spring actuated bellows, means in the bellows for allowing a quick transfer of fluid between bellows and chamber when bellows is operated upon by external member, the walls of the bellows allowing a slow transfer of fluid between chamber and bellows when spring actuated bellows operates upon released external member.

7. In a slow motion mechanism, a fluid chamber, within the fluid chamber a spring

actuated bellows, an external member for operating the bellows and when released operated by the spring actuated bellows, a valved opening in the bellows for allowing 5 a quick transfer of fluid between the bellows and chamber when the bellows is operated upon by the external member, the walls of

the bellows of flexible porous material for allowing a slow transfer of fluid between chamber and bellows when spring actuated 10 bellows operates upon released external member.

CLYDE F. McCANN.
